UNITED STATES PATENT OFFICE.

WILLIAM SCOTT, OF WARRIOR, ALABAMA.

RAIL-JOINT.

1,195,406.

Specification of Letters Patent.

Patented Aug. 22, 1916.

Application filed February 1, 1916. Serial No. 75,525.

To all whom it may concern:

Be it known that I, WILLIAM SCOTT, a citizen of the United States, residing at Warrior, in the county of Jefferson and 5 State of Alabama, have invented certain new and useful Improvements in Rail-Joints; and I do declare the following to be a full, clear, and exact description of the invention, such as will enable others skilled in the art 10 to which it appertains to make and use the same.

This invention relates to improvements in rail joints, and has for its object the production of a simple and effective joint, and one 15 which can be very inexpensively manufactured.

Another object of the invention is to provide a device of this character embodying such features that the joint may be made 20 rigid and all parts positively locked against separation.

Still another object of the invention is to provide a simply constructed device of this character which can be quickly and easily 25 secured to the meeting ends of a pair of rails.

With the foregoing and many minor objects in view, the invention resides in the novel features of construction, combination 30 and arrangement of parts which will hereinafter be more particularly described and claimed and shown in the drawings wherein:—

Figure 1 is a plan view of one of my improved rail joints showing the meeting ends 35 of a pair of rails held therein; Fig. 2 is a side elevation of the parts shown in Fig. 1; Fig. 3 is a vertical transverse section taken on the line 3—3 of Fig. 2; Fig. 4 is a similar 40 view showing the locking means in inoperative position; Fig. 5 is a horizontal section taken on the line 5—5 of Fig. 3; Fig. 6 is a similar view taken on the line 6—6 of Fig. 4; Fig. 7 is a perspective view of the rail 45 chair with the locking means removed; Fig. 8 is a similar view of one end of the rock shaft; and Fig. 9 is a detail perspective view of the wrench used in rotating the 50 shaft shown in Fig. 8.

In its preferred embodiment, my invention comprises a chair 1 in which the ends 55 of the rails R are disposed, said chair comprising a base plate 2 which rests upon the ties and beneath the base of the rails. Rising from this base plate 2 are fish plates 3 which extend upwardly on opposite sides

of the rails R and engage the under side of the head and the web thereof. These fish plates and the base plate 2 are preferably cast in one piece, thus providing an extremely strong chair, but one which can be very easily placed around the rails. In placing the chair in position it is first slid onto one rail, and then the adjacent rail is moved until its end contacts with the end of the first-mentioned rail, when the chair can be moved in a direction to dispose it in engagement with both rails.

The usual bolt receiving openings 4 in the webs of the rails aline with similar openings 5 in the fish plates for the reception of locking pins or bolts 6. In the ordinary rails there are two bolt openings adjacent each end; therefore in the chair I provide four openings to aline with the openings 4 and 5, or easily removed therefrom when it becomes necessary to disengage the ends 80 of the rails.

For the purpose of moving the pins 6 into and out of engagement with the openings 4, I provide a rock shaft 7 which is rotatably mounted in bearings 8 formed in the spaced apart ears 9, said ears projecting from one of the fish plates as shown and are preferably integrally formed therewith. The ears 9 are disposed at the opposite ends 90 of the fish plate and support the ends of the rock shaft 7, one of said ends projecting beyond the adjacent ear and squared as shown at 10 to receive a suitable wrench 10' for rotating the shaft. This shaft has the outer projecting ends of the pins 6 pivotally 95 connected therewith by any preferred means so that when said shaft is rotated in the proper direction, the pins will either be simultaneously removed out of operative engagement with the openings in the web of 100 the rails, or moved in such a direction as to lock the ends of the rails and the chair together.

The means for pivotally connecting said rock shaft and the pins consists in providing 105 apertured lugs 11 which project at intervals from the shaft 7 in alinement with the openings 5 in the fish plates. All of these lugs 11 project in the same direction from the shaft 7 and are disposed between the furcations 12 of the bifurcated heads 13 formed on the ends of the pins 6, pivot pins 14 being

passed through the apertures in said lugs and through openings alined therewith in the furcations 12. The heads 13 being considerably larger than the openings 5, they 5 will contact with one fish plate and prevent the pins from being moved through the openings 4 and 5 to such an extent as to cause the parts to bind.

One end of the rock shaft 7 is flattened as 10 shown at 15 to provide parallel faces, and the ear 9 adjacent this flattened end is provided with a slot 16 which communicates with the opening 8 therein as shown in the drawings. When the rock shaft has thrown 15 the pins 6 into locking engagement with the openings in the webs of the rails, the flattened end thereof will be disposed in the slot 16 which also has parallel walls and is of a size to readily receive the said flattened 20 end, yet prevent rotation thereof. This arrangement will prevent the pins from becoming accidentally disengaged from the rails and positively lock all parts until the rock shaft is manually raised out of engagement with the slot 16 and rotated.

The rock shaft has sufficient lateral movement to readily allow its flattened end to successfully operate the pins when moved out of the slot and into the bearing opening 30 8. After the pins have been withdrawn, the shaft will be retained in the bearing opening until it is again rotated to throw the pins into their locked position.

From the foregoing description, it will be 35 seen that I have invented a very simply constructed rail joint formed from a chair upon which is mounted means for simultaneously projecting or retracting the locking pins.

While I have described the invention with 40 a considerable amount of detail, it is obvious that various changes may be made in the form and proportion of the various parts without departing from or sacrificing any of the principles of the invention.

45 I claim as my invention:

1. In combination with the meeting ends of a pair of rails; of a chair having a plurality of openings alined with the openings in the rails, locking pins slidable through 50 said openings, a rock shaft rotatably mounted on said chair, and a pivotal connection between said rock shaft and the pins, whereby the same may be thrown into or out of engagement with said openings in the rails.

55 2. In combination with the meeting ends of a pair of rails; of a chair having a plurality of openings alined with the openings in the rails, locking pins slidable through said openings, bifurcated heads on one end 60 of said pins, a rock shaft rotatably mounted on said chair, apertured lugs on said shaft

for pivotal engagement with said bifurcated heads, and a keeper for engagement with one end of said shaft to prevent rotation thereof.

3. In combination with the meeting ends 65 of a pair of rails; of a chair having a plurality of openings alined with the openings in the rails, locking pins slidable through said openings, a rock shaft rotatably mounted on said chair, one end thereof being adapted to move laterally, a keeper adjacent one end of the shaft to receive the laterally movable end to prevent rotation thereof, and a pivotal connection between said rock shaft and the pins, whereby the same may be 70 thrown into or out of engagement with said rails.

4. In combination with the meeting ends 75 of a pair of rails; of a chair having a plurality of openings alined with the openings 80 in the rails, locking pins slidable through said openings, a rock shaft having one end provided with flat faces, a pair of spaced apart ears on one side of said chair, said ears having openings to rotatably receive said 85 rock shaft, one of said openings communicating with a slot to normally receive the flattened end of the shaft to prevent rotation thereof, and a pivotal connection between said shaft and the pins, said flattened 90 end of said shaft being movable from said slot to allow rotation thereof to shift said pins.

5. In combination with the meeting ends 95 of a pair of rails; of a chair comprising a pair of fish plates to embrace the web and the base of a rail, a base plate connected therewith, said fish plates having a plurality of openings alined with the openings 100 in the rails, locking pins slidable in said openings, bifurcated heads on one end of said pins, a rock shaft having one end provided with flat parallel faces, apertured lugs projecting from said shaft and disposed between the furcations of said heads and 105 pivotally connected therewith, a pair of spaced apart ears on one side of said chair, said ears having openings to rotatably receive said rock shaft, one of said openings 110 in the ears having a slot with parallel walls communicating therewith, the flat end of said shaft being normally disposed in said slot to prevent rotation thereof, said flattened end being movable out of said slot to 115 allow rotation of the shaft.

In testimony whereof I have hereunto set my hand in presence of two subscribing witnesses.

WILLIAM SCOTT.
